F. B. SPRY

DRILL MOUNTING

Filed Aug. 21, 1922

55

Franklin B. Spry,

James L. Domé,
Attorney

UNITED STATES PATENT OFFICE.

FRANKLIN B. SPRY, OF PLYMOUTH, PENNSYLVANIA.

DRILL MOUNTING.

Application filed August 21, 1922. Serial No. 533,320.

To all whom it may concern:

Be it known that I, FRANKLIN B. SPRY, a citizen of the United States, residing at Plymouth, in the county of Luzerne and State of Pennsylvania, have invented new and useful Improvements in Drill Mountings, of which the following is a specification.

This invention relates to drill mountings, particularly adapted for coal drills, and the primary object of the invention is to provide a simple frame structure over which the motor carrying the drill bit is longitudinally adjustable by manually controlled means to regulate the penetration of the drill bit relatively to a hard or soft substance or strata encountered during the drilling operation without requiring the substitution and use of feeding bars or screws having different threads. A further object of the invention is to provide a drill mounting having a feeding thread bar or screw separable feed nut formed with threads only at the lower portion thereof and connected to a motor carrying and operating the drill bit, to permit full disengagement of said nut from the feeding bar or screw for quick return of the motor and bit to starting position by a simple manipulation. A still further object of the invention is to provide a drill mounting with a driving bar or holding wedge and with adjustable and foldable legs or supporting means which respectively allow adjustment of the drill bit and motor at any desired angle and elevation and also permit the parts of the mounting to be collapsed or reduced to compact form for ready transportation by one man to and from and about different parts of a mine or other place.

With these and other objects and advantages in view, the invention consists in the construction and arrangement of the several parts which will be more fully hereinafter described and claimed.

In the drawings:—

Fig. 1 is a side elevation of the improved drill mounting and drill accessories shown applied in working position;

Fig. 2 is a top plan view of the improved drill mounting and drill accessories with the legs illustrated as folded and the parts as a whole reduced to compact form;

Fig. 3 is a sectional perspective view of

the forward extremity of the improved mounting and the driving bar or holding wedge; and

Fig. 4 is a transverse vertical section on the line 4—4, Fig. 1, showing parts of the mounting broken away.

The improved mounting comprises bars or guide rods 5 and 6 secured at their ends to cross heads 7 and 8 of special form. Each cross head has upwardly and outwardly inclined arms 9 in the terminals of which the guide rods 5 and 6 are secured.

The arms 9 are continuous with depending bodies 10 and 11, the body 10 of the cross head 7 being practically semicircular and having an opening 12 therethrough, and the body 11 of the cross head 8 being essentially rectangular and depending below the body 10 and having a right angular foot 13 with an opening 14 therethrough. The body 11 of the cross head 8 also has an opening 15 therethrough adjacent to the juncture of the arms 9 with the body. The opposite terminals of the arms 9 of the cross head 7 are directed forwardly to serve as right angular supports 16 in which leg sockets 17 are swiveled, each of the said sockets having a transversely extending opening 18 therethrough intersected by a longitudinal screw-threaded opening 19 to receive a clamping screw 20 provided with a small clamping bar 21 which is loosely movable through the head 22 of the said screw. In the openings 18 of the swiveled sockets 17 reversible legs 23 are adjustably mounted, the said legs having their opposite ends 24 pointed so that either end of each leg may be engaged with the supporting bed of a mine or other base means over which the improved drill mounting and drill accessories may be disposed. The legs 23 are freely slideable through the openings 18 in the sockets 17 and may be clamped and held fixed at different projecting lengths from their sockets by the screws 20.

Mounted on the guide rods 5 and 6 is an electric motor 25 of any approved and desirable type and having current feeding wires 26 adapted to be connected to a suitable source of current generation. The motor 25 has opposite pairs of apertured guide projections 27 through which the guide rods 5 and 6 extend, these projections being separated by an open space 28 to reduce the friction.

tion between the said projections and the guide rods during the shifting movement of the motor 25 in opposite directions. Below the motor 25 a feeding threaded bar or screw 5 rod 29 is swiveled in the openings 12 and 15 of the bodies 10 and 11 of the respective heads 7 and 8. The rear end of the bar or rod 29 is reduced and projects rearwardly from the cross head 7, as at 30, and is provided with a crank handle 31 by means of which the said bar or rod may be manually rotated to control the feed of the motor 25 longitudinally on the guide rods 5 and 6. The motor shaft is provided at its forward 10 end with a tool holding socket and clamp 32 adapted to removably receive the shank 33 of a drill bit 34 which has free movement centrally between the arms 9 of the front cross head 8.

20 The casing or frame of the motor 25 has a central depending extension 35 at the bottom thereof, the said extension forming part of the nut for engaging the threaded bar or screw rod 29, and for this purpose this extension is formed with a semicircular smooth channel 36, as clearly shown by Fig. 4. At one side of the centre of the extension 35 a movable nut member 37 is pivoted and has a semicircular threaded channel or groove 38, 25 the bottom of the pivoted nut member 37 adjacent to the inner side edge thereof having an inclined catch enlargement 39 for engagement by an angular catch projection 40 at the inner portion of the lower extremity 35 of a catch 41 pivoted to the extension 31 at a point opposite to the attachment thereto of the pivoted nut member 37. The catch 41 has a lower outwardly projecting gripping extension 42 by which it may be easily operated to effect an engagement and disengagement thereof relatively to the pivoted nut member 37.

Depending from the angular foot 13, forming part of or secured to the body 11 of the front cross head 8, is a pin or post 43 secured at its upper end in the opening 14 of the said foot, and having the lower end screw-threaded, as at 44, to receive a nut 45. This pin or post 43 is provided for attachment to the improved mounting of a driving bar or holding wedge 48 which has its front extremity 46 tapered and polygonal in contour in cross section. The rear extremity of this driving bar or holding wedge is formed 50 with an elongated oval opening 47 therethrough to receive the pin or post 43, and when the nut 45 is applied to the lower screw-threaded extremity 44 of the pin or post the driving bar or holding wedge will have loose association with the pin or post to permit the remaining portion of the drill mounting and drill accessories carried by the mounting to be adjusted at any angle desired to drill. It will be seen that the elongated form of the opening 47 of the driving

bar or holding wedge 48 permits the pin or post 43 to assume different angular positions therein without displacement and resetting of the said bar or wedge. The elongated opening or slot 47 in the rear extremity of the driving bar or holding wedge 48 also permits the said bar or wedge to be driven into the wall of material to be drilled, to tighten the same during the time that it is associated with the pin or post 43 without in the least jarring or injuring the frame or the drill accessories carried thereby, and furthermore, the angular foot 13 is fixed to the front portion of the body 11, or the front cross head 8, and the pin or post 43 is immovably secured to the lower front extremity of the said foot and the position of the pin is never varied relatively to the foot.

In applying the improved drill mounting and drill accessories for operation, a starting opening is formed in the coal vein or part of the mine wall adjacent to the vein, or in other material, by means of the drill bit, and the driving bar or holding wedge 48 is then driven into said opening and is permanently secured in view of the polygonal cross sectional contour of the front tapered extremity thereof. The remaining part of the mounting and drill accessories including the motor 25 and drill bit 34 may then be set horizontally or at any angle desired by adjusting the legs 23 and fixing the adjustment of said legs in the sockets 17. In starting the drilling operation the motor 25 carrying the drill bit 34 will be drawn rearwardly the required distance by first detaching the latch 41 from the pivoted nut member 37 and thereby separating the threaded channel or groove 38 from the threads of the bar or rod 29. After the motor has been drawn back manually the required distance on the guide rods 5 and 6, and which movement will be readily permitted in view of the fact that the channel or groove 36 is not threaded, the pivoted nut member 37 is then turned up in a position to cause the threaded channel or groove 38 thereof to fit over the threaded bar or rod 29, the nut member being secured in this position by causing the latch 41 to engage the same. The motor 25 is then started by turning on the current thereto and the drill bit 34 is given a penetrative operation by manual adjustment or rotation of the bar or rod 29 through the crank handle 31. If, during the course of penetration of the drill bit 34 over the coal vein or other substance drilled, a hard or very soft substance is engaged, the operator may regulate the rapidity of penetration of the drill bit by decreasing or increasing the forward feed thereof, or regulate the degree of rotation of the threaded bar or rod 29 in accordance with the character of the hard or soft substance encountered. During the drilling operation the

mounting will be held up in position by the driving bar or holding wedge 48, and as hereinbefore intimated the improved mounting as a whole together with the motor 25 and drill bit 34 may be adjusted at different angles while the driving bar or holding wedge is retained in the position in which it was originally applied. When it is desired to transport or move the improved drill 10 mounting and motor 25 and drill bit 34 from one point to another for resetting or reapplication thereof, the driving bar or holding wedge 48 is withdrawn from its applied position and the legs 23 folded along the opposite 15 sides of the mounting as shown by Fig. 2 to reduce the entire improved structure to compact form, and in this reduced arrangement the complete device may be readily transported by one man and reset with facility. 20

The improved drill mounting and drill accessories are of comparatively light weight but at the same time are strong and durable. By using a hand feed of the character specified 25 it is possible to drill materials which could not be drilled with a positive feed and by the use of a feeding bar and open box such as is now commonly used. Moreover, by having the feeding bar or screw rod 29 under 30 manual control and regulable as hereinbefore specified, the drill is rendered capable of drilling both hard and soft material without the use and substitution of different thread bars or feeding screw rods.

35 It will be understood that changes in the proportions and dimensions and minor details of construction of the improved drill mounting may be adopted without departing from the principle of the invention.

What is claimed as new is:

A drill mounting of the class specified, comprising a frame having end cross heads each provided with upwardly and outwardly inclined arms and a depending body, guide rods secured in the upper divergent terminals of the inclined arms, the depending body of the front cross head continuing into a downward projection terminating in a right-angular foot having a forwardly projecting horizontal member with a depending pin rigidly held therein, a motor carrying drill accessories freely slideable on the guide rods, a hand operated screw extending through the openings of the depending boss of the cross heads, the lower portion of the motor being provided with means to separably engage the said screw, vertically and laterally adjustable legs associated with the rear cross head, and a wedge tapered at its front extremity for driving the same into the material to be drilled, the rear extremity of the wedge having an elongated opening extending vertically therethrough for loose attachment to the pin depending from the foot and permitting the said pin to move backwardly and forwardly and also to assume different angular positions in said elongated opening in the rear extremity of the wedge without displacing or resetting the latter. 60

In testimony whereof I have hereunto set my hand in presence of two subscribing witnesses.

FRANKLIN B. SPRY.
